UNITED STATES PATENT OFFICE.

BENJAMIN NICHOLS, OF JAMESTOWN, NEW YORK, ASSIGNOR TO THE AMERICAN AXE AND TOOL COMPANY, OF NEW YORK, N. Y.

BRUSHING, GRINDING, AND POLISHING MACHINE.

SPECIFICATION forming part of Letters Patent No. 651,492, dated June 12, 1900.

Application filed May 18, 1899. Serial No. 717,273. (No model.)

To all whom it may concern:

Be it known that I, BENJAMIN NICHOLS, a citizen of the United States of America, residing in Jamestown, in the county of Chautauqua, in the State of New York, have invented a certain new and useful Improvement in Brushing, Grinding, and Polishing Machines, of which the following is a true and exact description, reference being had to the accompanying drawings, which form a part thereof.

My invention relates to mechanism such as is used for brushing, grinding, and polishing, and is particularly designed for polishing axes, although well adapted for use with other articles of manufacture.

The object of my invention is particularly to provide means for subjecting all parts of an irregularly-shaped object, such as an ax, to a uniform brushing and polishing treatment and in this connection to place the movement of the object being treated completely in the operator's control, so that it can be shifted under the action of the brush or disks or held in position to be treated or out of position to be treated, as may be desired.

The nature of my improvements will be best understood as described in connection with the drawings in which they are illustrated, and in which—

Figure 1 is a rear view of the machine; Fig. 2, an end view; Fig. 3, a horizontal section taken as on the line 3 3, Fig. 1. Fig. 4 is a front view of the machine; Fig. 5, a top view with the main driving-belt partially cutaway. Figs. 6 and 7 are respectively a side elevation and a plan, on a larger scale, of details shown in Figs. 4 and 5. Fig. 8 is a section on line 8 8 of Fig. 7, and Fig. 9 illustrates a modification.

The frame of the machine is indicated by the uprights A A, topped by laterally-projecting cross-pieces A'.

A² A³ are cross-pieces of the framing, serving to support certain operative parts; A⁴, a vertical guide.

B B are horizontal guide-pieces supported on the cross-pieces A³ A³.

C and C' are sliding platforms supported on the guides B B and each supporting in turn shaft-bearings, as indicated at C² C².

C³ C³ indicate bars adjustably secured to the platform C and C' and supporting at their inner ends rollers C⁴ C⁴.

To the inner ends of the platforms C and C', as indicated at C⁵ C⁵, are secured cords C⁶ C⁶, 55 to the ends of which in turn are secured weights C⁷, which tend to draw the two platforms together.

C⁸ indicates a pulley over which one of the cords C⁶ passes.

D and D' are parallel shafts secured in the shaft-bearings C² of the platforms C and C'. Each of these shafts supports a pulley-wheel, as indicated at D² D³, and has secured to its outwardly-projecting end a grinding, brushing, or polishing disk, as indicated at D⁴ and D⁵, where they are shown as polishing-disks, or at d⁴ d⁵, Fig. 9, where they are shown as brushes. These disks or brushes of course follow the motion of the platform C and C' 70 and are normally drawn together or toward each other by the action of the weights C⁷ C⁷.

E E are levers pivoted to the frame at E' and having shaft-bearings at their inner ends.

F is the main driving-shaft of the machine. 75 To it are secured the pulley F', through which power is applied to drive the machine, the main driving-pulley F², by which the power is transmitted, as will be described, to the disks, and a pulley F³, by which power is transmitted to other operative parts of the machine.

G is a shaft secured in the bearings attached to the cross-pieces A' and supporting a pulley G'.

H and h are shafts secured in bearings supported on the cross-bars A² and supporting-pulleys H' and h'. I is a shaft also supported by the cross-bars A², and to which is secured a pulley I'.

J is a shaft supported on the free ends of the levers E and having secured to it a pulley J'. This pulley, it will be understood, is in the nature of a take-up pulley.

K is the main driving-belt, which, following the direction of the arrows, passes from the under side of the pulley F², over the pulley H', thence under the pulley D³, thence over the pulley I', thence under the take-up pulley J', thence over the pulley h', thence 100

under the pulley D², thence over the pulley G' back to the main pulley F², as shown. This arrangement of the pulleys and belt is such as will permit the platform C and C', carrying the brushes d⁴ d⁵ or polishing-disks D⁴ and D⁵, to move away from or toward each other without in the least affecting the transmission of power to the pulleys.

L is a shaft, which, as shown, (see Fig. 7,) 10 has a bearing L² of such a character as to give it a certain angular freedom of motion and a second bearing L³, (see Figs. 6 and 8,) supported and moving on a slide, as indicated at l³. Secured to the shaft L is a pulley L', 15 which is driven from the pulley F² on the shaft F by means of a belt M and drives a friction-pulley drum L⁴, also secured to shaft L.

N is a shaft also supported on the cross-pieces A' and having secured to it friction 20 pulley or drum N', lying immediately in front of the friction-pulley L⁴, and also a gear-wheel N², which is engaged with a gear-wheel O², secured in turn on a shaft O, having at its other end a crank-disk O', carrying a crank-pin O³.

Q² is a brake arranged in front of the friction-drum N' and secured to a lever Q', pivoted at Q.

P is a rod connected with the ends l and q 30 of the shaft L and lever Q', and also connected, as shown, with the short arm P² of the bell-crank lever P² P³, pivoted as indicated at P', and by turning which it is obvious the friction-drum L⁴ and brake Q² will be 35 simultaneously shifted in the same direction with reference to drum N', the effect being to bring either the friction-wheel or the brake into contact with the drum N', the contact of the two friction-drums effecting the revolution of the shafts N and O, and the contact 40 of the brake with the drum N' at once arresting this motion and holding the parts in the position at which the brake takes effect.

P⁴ is a spring normally acting to draw the arm P³ of the bell-crank lever upward and to hold the brake Q² in contact with the drum N' and the positively-actuated drum L⁴ out of contact.

P⁵ is a rod extending downward from the arm P³ of the bell-crank lever to a treadle P⁶, pressure on the treadle shifting the position of the bell-crank lever and of the rod P, so as to bring the positively-actuated drum into 55 contact with the drum N' and release the brake Q².

R is a sliding head moving on the guide A⁴ and actuated from the crank-pin O³ by the connecting-rod R'. To the front of the slide 60 R is secured a downwardly-extending slide R², to the bottom of which in turn is attached an outwardly-extending arm R³, holding in turn an upwardly-extending work-holder device, (indicated at R⁴.) From the back 65 side of the slide R extends a disk-shifting device, (indicated at R⁵.) and which, as shown, has the form of a wedge. This shifting de-

vice passes between the rollers C⁴ C⁴, attached to the adjustable bars C³ C³, and as this shifting device is moved up and down it will be 70 obvious that the platforms C and C' and the disks supported thereon will be moved out or in in conformity with the shape of the shifting device R⁵, which device can be given any form which may be desirable to cause 75 the movements of the disk to conform with greater or less accuracy to the form of the article being brushed or polished.

In operation the belt K is in constant motion and the operating-disks in constant revolution. When an ax or other article is to be brushed or polished, it is placed or supported on the work-holding device R⁴, and the operator then draws down the arm P³ of the bell-crank lever, as by placing his foot on the treadle P⁶, shifting the positively-actuated drum L⁵ into contact with the drum N', and releasing the brake Q². This at once causes the revolution of the crank-disk O', and through the mechanism described causes the work-holding device R⁴ and the disk-spreading device R⁵ to reciprocate, carrying the work up and down between the disks D⁴ and D⁵, which disks are moved to and away from the work and from each other by the shifting 90 mechanism and in accordance with the form of this mechanism, which, as stated, should conform more or less closely to the form of the article under treatment. The ax or other article being treated can be arrested in any 100 position by simply releasing the pressure on the treadle, whereupon the positively-actuated drum is moved out of contact and the brake Q² into contact with the drum N'.

Having now described my invention, what 105 I claim as new, and desire to secure by Letters Patent, is—

1. The combination of two operative disks, as D⁴ D⁵, means for supporting and operating said disks arranged to permit them to move 110 freely to and from each other, a reciprocating disk-shifter, a work-holder reciprocating synchronously therewith, positively-actuated means for actuating the disk-shifter and work-holder and means under the control of the 115 operator for rapidly engaging and disengaging said reciprocating device.

2. The combination of two operative disks, as D⁴ D⁵, means for supporting and operating said disks arranged to permit them to move 120 freely to and from each other, a reciprocating disk-shifter, a work-holder reciprocating synchronously therewith, disengageable means for actuating the disk-shifter and work-holder and a brake operating alternatively 125 with said means for arresting them in whatever position they are in when disengaged.

3. The combination of two operative disks, as D⁴ D⁵, means for supporting and operating said disks arranged to permit them to move 130 freely to and from each other, a slide, as R, a work-holder moving with said slide, means for reciprocating said slide including shaft N and drum N', a positively-driven friction-drum

L^4 and a brake Q^2 arranged on opposite sides of drum N' and means for simultaneously shifting drum L^4 and brake Q^2 to bring them alternatively in contact with drum N' .

5 4. The combination of two operative disks, as $D^4 D^5$, means for supporting and operating said disks arranged to permit them to move freely to and from each other, a slide, as R , a work-holder moving with said slide, a disk-shifter also moving with said slide, means for reciprocating said slide including shaft N and drum N' , a positively-driven friction-drum L^4 and a brake Q^2 arranged on opposite sides of drum N' and means for simultaneously shifting

ing drum L^4 and brake Q^2 to bring them alternatively in contact with drum N' .

5. The combination with the shifting operative disks $D^4 D^5$ of the belt-pulleys $D^2 D^3$ attached to the shafts of the disks and moving with them, the driving-pulley F^2 , the fixed pulleys $H' h' G'$ and I' attached to the machine-frame, the take-up pulley J' and the belt K passing over said pulleys as described to operate the disks.

BENJAMIN NICHOLS.
